UNITED STATES PATENT OFFICE.

THEODOR HUGO, OF BERLIN, GERMANY.

MACHINE FOR MAKING PAPER BAGS.

1,021,778.

Specification of Letters Patent.

Patented Apr. 2, 1912.

Application filed February 25, 1910. Serial No. 546,002.

To all whom it may concern:

Be it known that I, THEODOR HUGO, engineer, and a subject of the King of Prussia, German Emperor, and a resident of Grü-
5 nauerstrasse No. 27, Berlin, in the King-
dom of Prussia and German Empire, have
invented certain new and useful Improve-
ments in Machines for Making Paper Bags
of which the following is a specification.

10 This invention relates to a machine for
making quadrilateral paper bags the special
feature of which is in the first place that
several paper bags of the same or different
15 sizes can be made at the same time, and in
the second place that the machine can be ad-
justed for different sizes of bag in the
simplest manner without having to dis-
mount or exchange parts of the machine,
20 this adjustment being effected simply by ad-
justing certain stops.

The paper bags are not made from a roll,
but from sheets, that is to say, a large number
25 of cut sheets of paper are stacked on a table
and are fed from this successively to the
machine. These blanks have the shape
shown in Figure 1 of the accompanying
30 drawings, the edge 1-2 being turned
toward the machine. The bags are made by
first folding the blank of the shape shown
in Fig. 1 on the line 3-4 so that it takes
35 the form shown in Fig. 2. The end flap 5
and the side flap 6 are then turned over and
gummed down to make the finished bag
shown in Fig. 3. On this bag there is
40 therefore a side seam and a bottom seam.
It will be seen from Figs. 2 and 3 that the
bottom has a powder-tight seal at the corner,
since the paper, owing to the form shown
45 in Fig. 1, folds upon itself double and so
forms at the corner a powder tight seal.

The machine for making the bag shown
in Figs. 1, 2 and 3 is illustrated in longi-
tudinal section in Fig. 4 and in plan in Fig.
5, Figs. 6, 7, 8, 9 and 10 are detail views
45 drawn to an enlarged scale and are ex-
plained hereinafter.

The blanks of the shape shown in Fig. 1
50 are stacked on a vertically adjustable table
7 (Fig. 4), the sheets of paper lying with
their edge 1-2 (Fig. 1) toward the ma-
chine. By means of a suction device 8 of
known kind, the top blank from the pile
55 resting on the table 7 is raised and then
seized by the grippers 10 and drawn on to
the folding table 11. The edge 1-2 (Fig.
1) of the blank strikes against an adjust-

able stop, not shown in the drawing but ar-
ranged on the folding table 11 in the plane
A B, and is maintained in its proper posi-
tion thereby. There then follows a down-
ward movement of a blade 12, which is fixed
60 to the lever 13 turning on the shaft 14. In
this manner the blank on the folding table
11 is carried between the rollers 15 and 16
and is folded on the line 3-4 (Fig. 1). 65
The folded blank, now having the shape
shown in Fig. 2, is led from the rollers 15
and 16 to the rollers 17 and 18 between a
pair of conveyer bands, of which the upper
one 19 passes from the roller 16 over the 70
tension roller 20 under tension rollers
21, 22 to roller 17 and returns under roller
23 to the roller 16. The lower conveyer
band 24 passes from roller 15 under roller
16 and then, like band 19, over tension roller 75
20, under tension rollers 21, 22, to roller 18,
whence it passes under the tension roller 25,
over the rollers 26, 27, under roller 28, over
roller 29, and under roller 30 back to roller
15. Several such conveyer bands are ar-
ranged in pairs on the rollers mentioned and
25 at certain distances apart as shown in Fig.
5. Thus the folded blanks arriving between
the rollers 15 and 16 are carried along by
the pairs of conveyer bands over roller 20,
under rollers 21, 22 between the rollers 17 80
and 18. There, as shown in Fig. 4, the
blank is released for a short distance and
arrives above the gum pot 32 and over
roller 26 to the lower conveyer band 24 and 85
by this is carried to the gumming device 31.
The gum pot consists essentially in a trough
32 bent at a right angle. Above the gum-
ming device 31 is an adjustable stop (not
90 shown) in the plane C-D against which 95
the edge 3-4 of the blank, carried along by
the conveyer band 24 and already folded to
the shape shown in Fig. 2, strikes; the
folded sheet is thus retained in this posi-
tion, with its flaps 5 and 6 (Fig. 2) above 100
the trough 32. The gummer, consisting of
a bar or the like shaped like the trough 32
and having been previously lowered until it
dipped in the trough and then raised again,
now descends to transfer gum from its 105
lower edge to the flaps 5 and 6. The ad-
justable stop is then lowered so that the
sheet can be carried on farther by the con-
veyer band 24 to the folding device 33. The
latter is shown to an enlarged scale in Figs. 110
6, 7, 8, 9 and 10 and consists in a number of
levers 35, 36 and 37 operating like tongs and

arranged side by side. The upper levers 35 are connected together on the underside by a plate 35^a, the lower levers 36 on their upper side by a plate 36^a. The lower levers 36 together with their connecting plate 36^a are first raised until their front edge is flush with the folder 38. The folded blank (Fig. 2), the flaps 5 and 6 of which, as above stated, have been duly gummed, is delivered 10 by the conveyer band 24 on to plate 36^a and remains with its edge 3—4 against an adjustable stop in the plane E—F in which position the line 1—2 (Fig. 2) coincides with the front edge of the plate 36^a. In 15 this position the upper levers 35 which, as already stated, are connected together on the underside by plate 35^a, press on the blank resting on the plate 36^a. In the closed position the levers 35 and 36 move downward around the shaft 39, whereby the flap 6 (Fig. 2) is bent as it passes against the edge of the folding flap 38. The movement 20 of the levers 35, 36 continues until plate 36^a is flush with the axis 38^a of the pivot of the folder 38. This movement is shared by the lever 37; the levers 35 and their plate 35^a then move upward, whereupon the folder 38 turns through an angle of 90° around the axis 38^a, completely folds over the previously 25 bent flap 6, sticks it down, and then returns. By the upward motion of the levers 35 and 37 the folded sheet on the plate 36^a is not completely released, since it is still held by 30 flat springs 43, 44 respectively carried by these levers. The lever 37 then moves downward alone. As soon as this lever rests on the plate 36^a, this plate with lever 36 and lever 37 moves downward so that the folded 35

sheet is bent when passing edge 40 of folder 41, which is a duplicate of folder 38. After 40 flap 5 has thus been upturned and after lever 37 has been raised off plate 36^a, folder 41 is rotated through 90° to fold flap 5 against the blank and paste it thereto. The bag is now finished and lever 36 with plate 45 36^a descends as shown in the dotted lines in Fig. 7 for the purpose of allowing the finished bag to fall on to the receiving devices of any suitable known kind.

Having now particularly described and 50 ascertained the nature of my said invention and in what manner the same is to be performed, I declare that what I claim is:

A machine for making paper bags comprising means for doubling a blank having 55 a side flap and a bottom flap, means for providing said flaps with an adhesive, means for conveying the doubled blank to a clamping device consisting of a plurality of substantially horizontal clamping levers, means for opening and closing said levers, a pivoted quadrantal side flap folder in front of the clamping device, a quadrantal bottom flap folder laterally flanking said device, means for intermittently lowering the 60 clamping device, and means for successively imparting a partial rotation to the folders, thereby consecutively folding the side flap and the bottom flap against the blank.

In witness whereof I have hereunto 70 signed my name in the presence of two subscribing witnesses.

THEODOR HUGO.
